DESIGN FOR A TIE-CLIP.

58,153.

Specification for Design.

Patented June 14, 1921.

Application filed January 27, 1921. Serial No. 440,504. Term of patent 14 years.

To all whom it may concern:

Be it known that we, FRED S. MAKER and RALPH K. MAKER, citizens of the United States, residing, respectively, at Seekonk, in the county of Bristol and State of Massachusetts, and at Providence, in the county of Providence and State of Rhode Island, have invented a new, original, and ornamental Design for a Tie-Clip, of which the following is a specification, reference being had to the accompanying drawings, forming a part thereof.

Fig. 2 is a side elevation thereof.

We claim:

The ornamental design for a tie-clip substantially as shown.

In testimony whereof we affix our signatures.

FRED S. MAKER.
RALPH K. MAKER.
